RECIPROCATING SANDING MACHINE

Eric Hartmann, deceased, late of Syracuse, N. Y., by
Clara Hartmann, executrix, Syracuse, N. Y., assignor
to Porter-Cable Machine Company, Syracuse, N. Y.,
a corporation of New York

Application February 20, 1956, Serial No. 566,506

5 Claims. (Cl. 51—170)

This invention relates to portable power-operated sanding machines of the reciprocating type.

The invention has as an object a bodily manipulable power-operated sanding machine of the reciprocating type embodying a light weight compact structural arrangement which is particularly economical to manufacture and which will operate over long periods of time without repairs or maintenance.

The invention consists in the novel features and in the combinations and constructions hereinafter set forth and claimed.

In describing this invention, reference is had to the accompanying drawings in which like characters designate corresponding parts in all the views.

In the drawings—

Figure 1 is a side elevational view of a sanding machine embodying my invention, the lower portion of the machine being shown in vertical section on a line corresponding to line 1—1, Figure 2;

Figure 2 is a view taken on line 2—2, Figure 1;

Figure 3 is a view taken on line 3—3, Figure 1;

Figure 4 is a view taken on line 4—4, Figure 1; and

Figure 5 is a view, similar to Figure 4, illustrating a modified form of bearing cup.

The machine consists of a base member having a top wall 10 with a flange 11 depending from the periphery thereof. The top wall is formed with a gear compartment 12, the lower end of which is provided with a closure cap 13 detachably secured to the base as by screws, one of which is shown at 14 in Figure 1. Aligned bearing bushings 15 are mounted in the top wall and cap 13 respectively, and a jack shaft 16 is journaled in these bearings and provided with a gear 18 arranged in the gear compartment 12 in mesh with a driving pinion 19 formed on the lower end of a power shaft 20.

A motor housing 22 formed with a handle portion 23 is mounted upon the top wall 10 of the base. A driving motor is mounted in the housing 22 with its power shaft 20 disposed vertically and extending into the gear compartment 12.

A pair of supports 24 depend from the top wall 10 in spaced apart relation. In the disclosure, the support members are in the nature of angle brackets formed from sheet material. The top wall 10 of the base being formed on its under side with pads 26 on which the supports are mounted and to which they are secured, as by screws 27. The supports 24 are formed at their lower ends with aligned apertures in which bushings 30 of wear resisting material, such as nylon, are mounted. The function of the supports 24 is to support an abrasive pad for reciprocation. The pad 32 is secured to a plate 35 which, in the illustrated form, is secured to an upper plate 36, as by screws 37 threading into apertures 38. The plate 36 is bent upwardly, as at 40, and laterally to provide the projections 39 of reduced width. The plate 36 is also formed with a plurality of downwardly extending projections 42 positioned in complementary apertures in plate 35, these projections and apertures forming

2

means for interlocking the plates and relieving the screws 37 of strain. A sheet of abrasive material 44 is positioned on the under side of the pad 32, the ends of the sheet being fixedly secured by suitable spring clamps 45.

5 The lower portion of the jack shaft 16, projecting downwardly from the gear compartment 12, carries an eccentric member 46. The lower end of the shaft 16 is formed with a flattened surface 48 and the bore of the eccentric 46 is of complementary shape whereby the eccentric is secured to the shaft against rotation relative thereto. The eccentric is encircled by an anti-friction bearing 49, the bearing being retained in position, and the eccentric retained on the shaft 16, by a washer 50 having its marginal portion overlapping the inner race of the bearing and being apertured to receive a screw 51 threading into the shaft 16, see Figure 1. The bearing 49 is enclosed in a cup-shaped member 54 and this member is positioned between a pair of lugs 55 extending upwardly from the plate 36, these lugs being economically provided in the form of portions or tabs bent upwardly from the plate 36. The cup member 54 is formed of anti-friction material, such as nylon, and the periphery of the side wall of the member may be of circular form, as shown in Figure 4. With this arrangement, the cup member 54 is free to rotate with the outer race of the bearing to effect uniform wear on the periphery of the cup member.

The peripheral surface of the cup member may be provided with a series of flat surfaces, as illustrated in 30 the hexagonal form shown in Figure 5. This arrangement provides a greater wear area engaging the projections 55 and, should a pair of these flat surfaces develop excessive wear, the cup member can be rotated to position another pair of the flat surfaces for engagement with the projections 55.

35 The eccentric member 46 is formed with integral counterbalancing sections 60, 61. These sections are of semi-circular form and serve to counterbalance the reciprocation of the pad structure.

40 What is claimed is:

1. A portable power-operated sanding machine of the reciprocating type comprising a base member having a top wall formed with a gear compartment, a motor mounted on said top wall and having a vertically disposed power shaft extending into said gear compartment, a jack shaft journaled in said gear compartment and having an end portion depending therefrom, a pair of spaced apart rigid bearing supports depending from said top wall and being fixedly secured thereto, said supports being formed with aligned apertures, an abrasive pad supporting plate having spaced apart portions offset upwardly from the plate and being slidably positioned in said apertures, means operatively connecting the lower end of said jack shaft to said plate and being operable 55 to effect reciprocation of said plate upon rotation of said jack shaft, and an abrasive pad carried by said plate.

2. A portable power-operated sanding machine of the reciprocating type comprising a base member having a top wall portion formed with a gear compartment, a 60 motor housing mounted on said top wall, a motor mounted in said housing and having its power shaft disposed vertically and extending into the gear compartment, a jack shaft journaled vertically in the gear compartment, and gearing arranged in said compartment and operatively connecting the power shaft of said motor to said jack shaft, said top wall having a pair of depending spaced apart rigid bearing supports fixedly secured thereto, said supports being formed with aligned apertures, an abrasive pad supporting plate having spaced apart portions, offset vertically from said plate, slidably mounted in said apertures, said plate being formed intermediate said offset portions with spaced apart upwardly extending lugs, an

eccentric member fixedly mounted on the lower end of said jack shaft and being cooperable with said upwardly extending lugs to effect reciprocation of said plate upon rotation of said jack shaft, and an abrasive pad carried by said plate.

3. A sanding machine as defined in claim 2 wherein said lugs consist of integral portions bent upwardly from said pad supporting plate.

4. A portable power-operated sanding machine of the reciprocating type comprising a base member having a top wall portion formed with a gear compartment, a motor housing mounted on said top wall, a motor mounted in said housing and having its shaft disposed vertically and extending into the gear compartment, a jack shaft journalled vertically in the gear compartment and gearing arranged in said compartment and operatively connecting the power shaft of said motor to said jack shaft, said top wall having a pair of depending spaced apart rigid bearing supports fixedly secured thereto, said supports being formed with aligned apertures, an abrasive pad supporting plate having integral vertically offset portions slidably mounted in said apertures, an eccentric secured to the lower end of said jack shaft, a bearing positioned on said eccentric, a cup-shaped member positioned on said bearing, said pad supporting plate being formed with a pair of upwardly extending projections disposed diametrically of said cup-shaped member and slidably engaging opposite sides thereof, and an abrasive pad carried by said plate.

5. A portable power-operated sanding machine of the reciprocating type comprising a base member having a

top wall portion formed with an enclosed gear compartment, a motor housing mounted on said top wall, a motor mounted in said housing and having its shaft disposed vertically and extending into said gear compartment, a jack shaft journalled vertically in the gear compartment, and gearing arranged in said compartment and operatively connecting the power shaft of said motor to said jack shaft, a pair of rigid bearing supports detachably secured to the top wall of said base member and depending therefrom in spaced apart relation, a bearing carried by each of said bearing supports, an abrasive pad supporting plate having integral vertically offset portions slidably mounted in said bearings, an eccentric secured to the lower end of said jack shaft, said pad supporting plate being formed with a pair of integral upwardly extending projections disposed in spaced apart relation, a bearing positioned on said eccentric, a cup-shaped member positioned on said bearing intermediate said upwardly extending projections and slidably engaging the same whereby to impart reciprocation of said pad supporting plate upon rotation of said jack shaft, and an abrasive pad carried by said plate.
